Application July 2, 1946, Serial No. 631,048

13 Claims. (Cl. 12—141)

2

1 This invention relates to shoe construction, and more particularly to a means for use in association with a last in the manufacture of shoes.

It has heretofore been a conventional practice in manufacturing shoes, whether of a closed heel type or open heel type, to place a last within the upper of the shoe and secure the back of the shoe to the back of the last at an appropriate height by means of tacks or nails or other securing means which penetrate the back of the shoe and secure the same to the last. The approved height for tacking has been established on the back of the last by a visual marker thereon, such as the head of a nail driven into and flush with the back of the last. This procedure not only mars the back of the shoe but also results in a time-consuming and somewhat inaccurate location of the top margin of the back of the shoe on the last, whether in shoes having back straps or open heels or in shoes having a closed heel type of construction.

Thus in the usual practice it has been necessary, in order to properly center the rear-most portion of the shoe upon the last, for a skilled operator to slip the back of the shoe over the last and hold the same in place while tacking guide-nails through the strap itself or at positions above or below the strap and into the last. Such tacking through the strap, quarter or counter of the shoe holds the upper relative to the last in an unyielding manner, which does not admit of subsequent adjustment of the upper and last if later desired unless the tacks are pulled. On the other hand, tacks above and below the back strap in the heelless type of shoe construction, while permitting the adjustment of the strap from side to side of the last during subsequent lasting operations, nevertheless require the time and attention of a skilled operator. Also such tacks must be inserted or removed for each lasted shoe, and furthermore permit adjustment sidewise only, and not vertically.

Thus it may be seen that the continued driving and removing of tacks or nails into the back of the last, which is generally made of wood, gradually roughens and cuts away the back portion of the last, sometimes to such an extent that shoes lasted thereon may not fit properly because the draft on the counter or rear strap of the shoe during the lasting operation draws said rearmost part forwardly so that the upper part of the counter or upper edge of the back of the shoe may be too tight on the finished shoe and so cut into or bind against the heel of a wearer. Said tacking operations also so roughen the rearmost

portion of the last as to scratch the inner surface of the back of the shoe and mar the fabric or other lining thereof, and in some cases may even leave splinters of wood there.

It is therefore one of the objects of this invention to provide a readily applied and easily released clamping mechanism by the use of which the back of the shoe may be simply yet firmly held in place but which, at the same time, will yield sufficiently to permit the back of the upper of a shoe to be slid from side to side for adjustment as desired during the lasting operation. Moreover, it is intended to provide a gripping means such that the back of the upper held thereby is neither deformed or perforated in the manufacturing operation.

Another object of this invention is to provide a new and improved means for slidably clamping the back of the shoe upon a last.

Another object of the invention is to provide a simple, new and improved means readily manipulable by unskilled operators for the purpose of positioning the back of a shoe on a last at a predetermined height.

Another object is to supply a mechanical stop so as to eliminate the necessity for a visual aid on the back of the last for establishing the height of the back of the shoe.

Another and further object of this invention is to provide a new and improved means by which shoes may be produced with greater economy, more rapidly, and without unnecessarily perforating and marring the shoe.

It is another object to eliminate the necessity of a skilled operator for centering the back of the shoe upon the last.

Another further object is to provide a new and improved means of securing the back of the shoe to a last which is quickly and universally applicable to all shoes having a uniform counter height, including shoes of the wedge type, arch type construction, and solid-heel types, as well as open-heel types.

Another object is to provide a novel construction for a rear clamp on a last combining the features of a clamp with that of a mechanical height-gauge.

Yet another object of this invention is to provide a lasting process in the manufacture of shoes which may be largely carried on by unskilled operators and which will permit the time of skilled operators to be utilized for some of the more time-consuming operations in the lasting and manufacturing process.

It is also an object of this invention to elimi-

nate some of the disadvantages associated with means having a like purpose in the prior art.

Other objects and advantages will appear and be brought out more fully in the following specification considered with reference to the accompanying drawings.

In the drawings:

Figure 1 is a side view, partially in section, of a last embodying this invention.

Figure 2 is a rear view of the back of the last of Figure 1, as viewed from the right-hand side thereof.

Figure 3 is a fragmentary plan view of the last, taken on the line 3-3 of Figure 1.

Figure 4 is a perspective view of the rear and side portion of a last embodying this invention, showing the means of applying a strap-type of shoe thereto.

Figure 5 is a view similar to Figure 4 illustrating the use of this invention in conjunction with a shoe having a closed-heel type of construction.

Figure 6 is a side elevation of the rear portion of a last, partially in section, embodying another form of this invention.

Figure 7 is a rear view of the last of Figure 6 taken from the right-hand side of said figure.

Figure 8 is a plan view of a blank used in the construction of a spring clip in the form of this invention illustrated in Figures 6 and 7.

Figure 9 is a detailed sectional elevational view of the heel portion of the last, illustrating another form of spring clip.

Figure 10 is a view similar to Figure 9 illustrating a further modified form of spring clip.

Figure 11 is a view of a prying tool which may be used in practicing the method of this invention.

Figure 12 is a fragmentary side sectional view of the rear portion of a last illustrating a still further modified form of spring clip.

Figure 13 is a plan view of the modified form of Figure 12, parts of the last being cut away to show the securing of the spring clip to the last.

Figure 14 is a view similar to Figure 13 illustrating an additional alternate method of securing the spring clip to the last.

Referring more particularly to the drawings, there is shown a last of a type used in shoe manufacture generally designated by the numeral 20 and comprising a toe or forward portion 21 and a heel or back portion 22. At the back portion 22 of the last, as illustrated, for example, in Figure 1, there is provided a spring clip 25 of roughly L-shaped appearance, a forward and upper leg 26 of which is disposed within a slot 27 formed in the upper part of the last and a rearward and downwardly extending leg 28 of which depends downwardly over the back 22 of the last and is normally urged thereagainst to clamp the back of a shoe or upper in place upon the last as hereinafter described.

Between the downwardly extending leg 28 and the back 22 of the last but disposed adjacent the upper part of said downwardly extending leg is a stop 31 constructed in a manner and for a purpose hereinafter explained.

The construction of the last in the preferred embodiment of this invention illustrated in Figures 1 through 5 is as follows:

The main body of the last 20 is most generally and preferably made of wood and is formed with a vertically disposed socket 32 having a metal liner 33 coextensive with its inner surface to permit slidable positioning of the last in an inverted position from that shown in Figure 1 upon the spindle of any one of several types of machines

employed in the production and lasting of the ultimate shoe. An outer cover 34 preferably of tough fibrous material such as leather extends over the upper back portion 22 of the last and surrounds the socket 32 and its liner 33. A spacer 35 which may be made of a material similar to the cover 34 is disposed beneath the cover and is formed with a substantially rectangular slot 36 extending from a point behind the socket 32 throughout the rearward part of the spacer. The slot 36 adjacent its forward end is formed with a smaller transverse slot 37 on both sides for the reception, by the slot 36, of the forward leg 26 of the spring clip 25 and by the slot 37 of a transverse pin 40. Said forward leg 26 is formed into a loop 42 normally loosely disposed within the slot 27 and is further provided with an upturned tip 43 normally bearing against the upper wall of the slot 27 in a manner to hold the bend 45 in the spring clip against the shoulder 46 provided at the outer lower end of the slot 27.

For the additional purpose of providing sufficient space within the slot 27 to accommodate the loop 42 at its forward end, the lower wall of said slot is slanted downwardly and forwardly. This construction, moreover, aids the keying action of the transverse pin 40 and serves to retain the forward end of the spring clip securely within the slot 27.

The lower and rearward leg 28 of the spring clip is formed into a terminal loop 48 into which the finger of an operator or the tip 50 of an instrument, as illustrated in Figure 11, may be axially inserted, by means of a handle 51, for drawing the spring clip away from the back of the last to permit the insertion of a strap 52 (Figure 4) of a shoe 53 or the counter portion 55 (Figure 5) of a shoe 56 thereunder.

The stop 31, positioned at the back of the last 40 just below the bend 45 in the spring clip, comprises a plate 60 secured to the back of the last as by means of nails 61 and provided with a pair of ears 62 on each side of the spring clip projecting rearwardly beyond the clip in a manner 45 to provide a stop above which the strap or counter portion of an upper may not extend when the same is slipped under the clip.

The use of the above described preferred embodiment of this invention illustrated in Figures 1 through 5, by way of example, may be as follows:

First referring to the manufacture of closed-heel shoes, and assuming that the several parts of an unassembled shoe comprising, for example, an insole, an upper, a counter, a midsole unit and an out-sole, may be disposed in a processing basket on an assembly line (not shown), and unskilled operator may apply a coating of slow-drying cement to the counter pocket at the back 60 of the upper and insert the counter therein in a manner well understood by those skilled in the art of shoe manufacture. This operator may also cement the inside bottom line of the upper. Subsequently, the insole may be temporarily attached to the bottom of the last as by tacking. An unskilled operator may also cement the bottom of the insole on the side opposite from the last and slip the rear part of the upper under the clip, thereby securing the same on the last for subsequent operations, such as lasting the cemented lower edges of the upper over the bottom of the insole.

The above-outlined procedure is an advance over the methods heretofore employed in that it has been necessary to go through substantially

the following procedure in the manufacture of closed-heel type shoes, a procedure which, it should be noted, has generally required the services of a skilled operator and is here set forth only by way of example:

The basket containing the necessary parts, as above noted, has passed before the skilled operator, who has removed the upper and last from the processing basket and, while holding the upper in an inverted position, has placed the counter in the counter-pocket. This operator has then placed a piece of oiled paper or similar material inside of the leather upper while slipping the last into place within the shoe so as to separate the rear portion of the upper from the back of the last, preventing the adhesion of the shoe and the upper at that point. The same operator has then placed the last in an inverted position upon the spindle of an assembly machine and, while aligning the upper with respect to the last, has moved the same into an assembly machine. Said assembly machine, upon the tripping of a lever by the operator's foot, has tacked the bottom of the toe and heel to secure the same to the bottom of the last and aligned and held the same upon the last. The resultant upper tacked to the last has then been replaced in the processing basket for subsequent operations.

It will therefore be seen that the proposed method of shoe construction employing the spring clip and other features of invention hereinabove described will eliminate the necessity of a skilled operator who has heretofore assembled the counter upon the upper, a process which has often required the initial removal of the upper from the last for the purpose of inserting the counter in the counter-pocket in closed-heel shoes. A portion of the skilled assembler's time may now be saved and may therefore be utilized in subsequent time-consuming operations, such as pulling the upper over the last and securing the same to the bottom of the insole.

Similarly, the present method of assembling shoes of the open-back type has been simplified by way of illustration, as follows:

The assembly basket containing the last and the parts of the unfinished shoe, namely, the upper (including a strap at the back, but having a heel portion cut out), the midsole and the outsole, is placed before the assembler, who has ordinarily been a skilled operator. This operator has been required to remove the last and upper from the processing basket, apply an oiled paper or the like to the back of the strap, assemble the upper over the last and slide the top line of the back strap to a nail-head or other visual location on the back of the heel and place one tack into the last at the top line and another at the bottom line of the back-strap to secure the same in place at the proper height upon the back of the last. In some cases, dependent largely on the type of shoe and strap, the operator has been required to tack into the material of the back strap itself after completing the task of aligning the upper upon and relative to the last.

By the present proposed method utilizing the teaching of this invention, it will be possible for an unskilled operator to cement the inside bottom line of an upper, assemble an insole to the bottom of the last, cement the bottom of the insole, and slip the back strap of the upper under the clip 25 attached to the last to the point established by the stop 31.

Thus, not only will the operation of aligning and assembling the upper on the last be simpli-

fied, but these operations may be accomplished by an unskilled operator instead of the skilled operator heretofore required, the height and side-wise adjustment of the upper relative to the last being readily and slidably achieved.

A modified form of combined spring clip and last which is susceptible of quick slidable attachment as well upon shoes having an arch or heel-type construction as upon shoes of the wedge-type construction is illustrated in Figures 6 through 8, and further modifications of this form of spring clip are illustrated in Figures 9 and 10.

First referring to the form of the invention illustrated in Figures 6 through 8, there is shown a last 100 formed with a vertical socket 101. Extending at an angle substantially vertically through the last is a bore 102 rearward of said vertical socket and slidably accommodating a removable screw 103 formed with an eyelet 104 at its upper end and having a lower threaded end 105. The function of the screw 101 is to permit the threadable affixation of a desired heel (not shown) of a shoe during the lasting operation. To carry out this purpose the screw 103 is former 15 with a collar 106 having a lower conical face 107 normally bearing against a pair of washers 108 which urge a rubber disc 110 downwardly against the upper face of a fibrous cover 111 secured upon the top of the last.

For the purpose of attaching the substantially L-shaped spring clip 115 to the last in the desired position, there is provided a slot 116 at the back of the last into which is snugly inserted a forward leg 120 of the spring clip. This forward end, as may be most clearly seen from the blank form of the same illustrated in Figure 8, is provided with an elongated slot 121 for the clearance of the screw 103 at an angle relative to said forward leg, and a smaller circular opening 122 back 20 of the slot 121 for the similar reception of a wood screw 125. The combination of screws 103 and 125 prevent excessive lateral movement of the spring clip 115 within the slot 116. Said clip is formed with a bend 126 disposed just back of the slot 116, 25 which serves as a vertical stop when the back of a shoe or upper is slipped under a back leg 128 of the spring clip, (the thickness of such upper is shown in phantom outline 129 in Figure 6) thereby obviating the necessity of a separate stop, 30 as provided in the preferred embodiment of Figures 1 through 5 hereinabove described. The back leg 128 of the spring clip likewise substantially parallels the back of the last, thereby serving to grip the back of the upper over a substantial area, and further avoiding any marring 35 or marking of the shoe. A terminal loop 140 in the lower leg of the spring clip provides a means for drawing the clip back away from the last, for inserting or removing an upper, as desired.

The manner of use of the spring clip illustrated 40 in Figures 6 through 8 is identical with the use which is intended to be made of the form of Figures 1 to 5, except that the bend 126 of the form of Figures 6 through 8 acts as a stop as 45 above noted, in lieu of the stop 31 of said first-named figures.

Figure 9 illustrates a modified form of clip 200, 50 provided at the rearmost portion of a last 201 formed with a slanting slot 202 cut in from the back of the last in a similar manner to the last 100 of Figure 6. The clip 200 contains a hole 205 for the reception of a wood screw 206 and a bore 210 therethrough for the slidable reception 55 of a heel-securing screw 211. The outer lower leg 212 of the spring clip is formed with a ter-

final finger-piece 213 formed in the shape of a hook for the purpose of enabling an operator more readily to spring the clip away from the back of the last, either with or without the aid of the tool, illustrated in Figure 11.

Figure 10 is similar to Figure 9, except that the terminal lower end 300 of the spring clamp 301 is turned outwardly and downwardly as a fingerpiece for the same purpose of facilitating the release of the spring clip from its normal position bearing against the rearward face of the last. A bend 302 in the clip provides a stop for the top back part of the shoe. A wood screw 303 extends through a hole 304 in the spring clamp and aids the heel-securing screw 305 to retain the forward end of the spring clip within the slot 306.

In the forms of the spring clip and last illustrated in Figures 6 through 10, the back of the last above the slot is chamfered at 120° above the clip to improve the flexing action of the spring as well as to prevent chipping of the back of the last above the clip.

In all forms of the spring clip a tack hole 130 may be provided which, however, need not be used except in unusual situations in which it may appear necessary to provide further securing of the upper to the last.

In the further modified form of combined last 400 and spring clip 401, as illustrated in Figures 12 and 13, the spring clip is again roughly L shaped and has an upper forward leg 402 formed with a forward loop 403 at the forward end of said leg. The last 400 may be constructed as in the previous embodiments with two layers of fiber 404 and 405 on its upper face. At the rear 406 of the last a downwardly slanting slot 407 is provided terminating and communicating at its forward end in a transversely disposed bore 408. The loop 403 and forward leg 402 of the spring clip are slidably insertable into the bore 408 and the slot 407, respectively, from one side of the last until the spring clip 401 is in axially centered position with respect to the longitudinal axis of the last and the rearmost leg 409 of the spring clip is at the center of the back of the last and normally spring-urged thereagainst by its own inherent resiliency.

The particular mode of construction of the last 400 and the spring clip 401, as illustrated in Figures 12 and 13, renders it convenient and economical to adapt a last of normal construction for the firm and permanent attachment of a spring clip which, while held firmly in position with relation to the last, may readily be removed for the purpose of replacement or renewal. Optionally, a plug 410, as shown in Figure 13, may be driven through the loop 403 after the clip 409 has been centered upon the last to bind the sides of the loop 403 more firmly against the walls of the bore 408 than if the body and resilience of the loop 403 were depended upon to bind itself in place, as for example, where the loop is made with an outside diameter larger than the bore so as to provide a squeeze fit of the former into the latter.

Figure 14 illustrates a last 450 having the same essential construction as the last of Figures 12 and 13 and likewise possesses a downwardly slanted slot 451 extending transversely entirely across the last in the manner of a saw cut similar to the slot 407 of Figures 12 and 13. A bore 452, however, does not extend entirely through the last from side to side but terminates after penetrating the last substantially over half its width. By

this construction a spring clip 453, in all respects similar to the spring clip 401 of Figures 12 and 13, is slidable laterally into the slot 451 and the bore 452 in a similar manner to the positioning of the spring clip 401 within the slot 407 and the bore 408 of Figures 12 and 13. It is obvious, however, that the clip 453 can be inserted within the bore and slot from only one side of the last. Thereupon a tapered plug 454 may be driven into the bore 452 in a manner to bind against the walls of the bore and also to penetrate a loop 455 formed in the forward leg 456 of the spring clip thereby holding the same in a firm relationship to the last.

In all forms of the spring clip illustrated in Figures 12 through 14 the rearmost portion of the forward leg 402 and 456, respectively, extends rearwardly beyond the back of the last to provide a clearance for the back of a shoe which may be clipped to the last and further provides a vertical stop similar to the stop 411 as illustrated in Figure 12.

It may therefore be seen that in the form of last construction and notation of Figures 12 through 14 the only essential implements for securing the spring clip to the last are an ordinary hand saw and a drill. The plugs 410 and 454 therein illustrated may optionally be omitted, and in either event the sides of the last at the entrance of the bore may be filled with a cementitious material, such as plastic or wood, and smoothed over so as to cover the opening of the bore, thereby serving at once to strengthen the connection between the spring clip and the last and also to avoid roughness and the possibility of snagging material upon an otherwise roughened surface.

While it is customary to make lasts of wood, this invention contemplates the use of lasts made from any other suitable material, such as plastic, hard rubber or the like, and while it is preferable to form the spring clip of a spring-type music wire or high-tension clock spring steel, it is obvious that the same could be made of any other suitable resilient material, such as reed or plastic. It has been found that a suitable spring clip may be formed from $\frac{3}{16}$ -inch thick annealed steel S. A. E. 1095 having a stainless coating thereon. The stop, if not formed as an integral part of the spring clip itself, may likewise be made of steel, plastic, wood, or the like.

The gist of this invention is the provision of a spring-type clip upon the back of the last, either associated with or integral with a suitable stop or guide. The utilization of this means has resulted in a new and improved shoe manufacturing process which is also a material part of this invention.

Although the invention has herein been shown and described in what is conceived to be the most practical and preferred embodiment, it is recognized that departures may be made therefrom within the scope of the invention, which is not to be limited to the details disclosed herein, but is to be accorded the full scope of the claims, so as to include any and all equivalent devices.

Having described our invention, what we claim as new and desire to secure by Letters Patent is:

1. A last for shoe construction, spring-urged means on the back of the last for releasably engaging and holding the back of a shoe upon said last, stop means associated with the spring-urged means limiting the extent to which the

back of the shoe may be inserted under said spring-urged means, and a finger piece upon said spring-urged means by which said last named means may be raised to slip the back of the shoe thereunder.

2. In the art of shoe construction, a last, a spring clip secured to the back of the last for releasably clamping the back of a shoe and a stop associated with the spring clip adapted to limit the extension of the back of the shoe under the spring clip.

3. In the art of shoe construction, a last, a spring clip secured to the back of the last for releasably clamping the back of a shoe and a stop associated with the spring clip adapted to limit the extension of the back of the shoe under the spring clip, said spring clip being formed with a terminal finger-piece substantially in the form of a loop adapted to receive a tool for lifting the spring clip to facilitate slipping the back of the shoe under the clip.

4. In the art of shoe construction, a last, a spring clip secured to the back of the last for releasably clamping the back of a shoe and a stop associated with the spring clip adapted to limit the extension of the back of the shoe under the spring clip, said last being formed at its upper rear portion with a substantially horizontal recess continuous with a substantially rectangular opening at the rear of the heel, said recess being of greater height at its inner end than its outer end and being formed with a substantially horizontal transverse keyway at its inner end, a first leg of said spring clip being disposed within the recess, said first leg being doubled back to form a loop and then curved to engage a wall of the recess in a manner to normally press a medial portion of the spring clip towards the wall of the opening and a second leg of the spring clip having a position against the back of the last, a pin in the keyway extending through the loop in the spring clip in a position to retain said first leg of the spring clip within the recess.

5. In the art of shoe construction, a last, a spring clip secured to the back of the last for releasably clamping the back of a shoe and a stop associated with the spring clip adapted to limit the extension of the back of the shoe under the spring clip, said stop comprising a plate secured to the back of the last and formed with at least one ear projecting backwardly adjacent the spring clip.

6. In a last for shoe construction comprising a heel and back portion on the last, the improvement which comprises a two-legged spring clip secured to the back portion of the last, said last being formed with a slot in said back portion, one leg of said spring clip being anchored within said slot and another leg of the spring clip depending downwardly over the back of the last and normally spring tensioned thereagainst.

7. In a last for shoe construction comprising a heel and back portion on the last, the improvement which comprises a roughly L shaped spring clip secured to the back portion of the last, said last being formed with an inwardly extending slot in said back portion, one end of said spring clip being anchored within said slot and the other end of the spring clip being bowed outwardly and depending downwardly over and against the back of the last, said other end of the spring clip being formed with a curved lower portion by means of which the spring clip may be manually urged out of its normal engagement against the back portion of the last, and stop

means associated with the spring clip adjacent an upper portion thereof outside the slot limiting the extent to which the back of a shoe may be inserted between the back of the last and said other end of the spring clip.

5. In a last for shoe construction comprising a heel and back portion on the last, the improvement which comprises a roughly L shaped spring secured to the back portion of the last, said last being formed with an inwardly extending slot in said back portion, one end of said spring clip being anchored within said slot and the other end of the spring clip being bowed outwardly and depending downwardly over the back of the last, said other end of the spring clip being formed with a curved lower portion by means of which the spring clip may be manually urged out of its normal engagement against the back portion of the last, and stop means associated with the spring clip adjacent an upper portion thereof outside the slot limiting the extent to which a back of a shoe may be inserted between the back of the last and said other end of the spring clip, said stop means being formed at the junction of the ends of the spring clamp.

9. In a last for shoe construction comprising a heel and back portion on the last, the improvement which comprises a spring clip secured to the last, said last being formed with a slot in said back portion, one end of said spring clip being anchored within said slot and the other end of the spring clip depending downwardly over the back of the last and normally spring tensioned thereagainst, said spring clip being formed in the approximate shape of a loop at said one end, said one end being normally urged against an upper wall of said slot and normally urging a body portion of said spring clip downwardly towards a lower wall of said slot in a manner to 40 tension the spring clip within the slot.

10. In a last for shoe construction comprising a heel and back portion on the last, the improvement which comprises a spring secured to the back portion of the last, said last being formed with a slot in said back portion, one end of said spring clip being anchored within said slot and the other end of the spring clip depending downwardly over the back of the last and normally spring tensioned thereagainst, said spring clip having said one end snugly inserted within said slot in a manner to prevent any substantial vertical movement of said one end therein, said spring clip having a downward bend just back of the rearmost edge of the slot forming an upper 45 limiting stop for the back of a shoe inserted under said other end of the spring clip.

11. In a last for shoe construction comprising a heel and back portion on the last, the improvement which comprises a spring secured to the back portion of the last, said last being formed with a slot in said back portion, one end of said spring clip being anchored within said slot and the other end of the spring clip depending downwardly over the back of the last and normally spring tensioned thereagainst, said spring clip having said one end snugly inserted within said slot in a manner to prevent any substantial vertical movement of said one end therein, said spring clip having a downward bend just back of the rearmost edge of the slot forming an upper 50 limiting stop for the back of a shoe inserted under said other end of the spring clip, and fastening means extending substantially vertically into a portion of said last and also through said one 55

end of the spring clip securely positioning said one end axially within said slot.

12. In a last for shoe construction comprising a heel and back portion on the last, the improvement which comprises a spring secured to the back portion of the last, said last being formed with a slot in said back portion, one end of said spring clip being anchored within said slot and the other end of the spring clip depending downwardly over the back of the last and normally spring tensioned thereagainst, said spring clip having said one end snugly inserted within said slot in a manner to prevent any substantial vertical movement of said one end therein, said spring clip having a downward bend just back of the rearmost edge of the slot forming an upper limiting stop for the back of a shoe inserted under said other end of the spring clip, said one end of said spring clamp having a plurality of spaced substantially vertical holes therethrough and screws extending through said holes so as to position said one end within the slot, at least one of said screws being slidably removable and serving to hold the heel of a shoe in place upon the last.

13. In a last for shoe construction comprising

a heel and back portion on the last, the improvement which comprises a two-legged spring clip secured to the back portion of the last, said last being formed with a slot in said back portion, one leg of said spring clip being anchored within said slot and another leg of the spring clip depending downwardly over the back of the last and normally spring tensioned thereagainst, said last being formed with a lateral bore communicating with a forward end of the slot and the forward end of said spring clip being formed into a loop adapted to fit slidably into said lateral bore, and a peg wedged into the loop binding the loop against the walls of the bore in a manner to secure the spring clip in place relative to the last.

HIRAM GORDON.
CHARLES H. FREE.
